UNITED STATES PATENT OFFICE.

JOHN POLHEMUS, OF NEW YORK, N. Y., ASSIGNOR TO R. HOE & CO., OF SAME PLACE.

IMPROVEMENT IN PRINTERS' IMPOSING-TABLES.

Specification forming part of Letters Patent No. 173,738, dated February 22, 1876; application filed January 19, 1876.

To all whom it may concern:

Be it known that I, JOHN POLHEMUS, of the city, county, and State of New York, have invented an Improvement in Printers' Imposing-Tables, of which the following is a specification:

The said improvement is fully illustrated in the accompanying drawings, which form a part of this specification, in which—

Figure 1 is a perspective view, and Fig. 2 a sectional view, showing the galley in use.

Heretofore the imposing-tables used by printers have consisted of a block of stone or iron mounted upon supporting-legs, and usually surrounded by a frame-work of wood to sustain it in place. Such tables have the iron or stone bed projecting considerably above the frame, ordinarily to the extent of one-half of an inch, and it has been impossible to transfer a body of composed types from a galley to said table, or vice versa, without seriously disturbing or "pying" such body of types.

It is the object of my invention to overcome this difficulty, and to so construct an imposing-table that a mass of composed types may be readily transferred therefrom into a galley, or vice versa, without danger of disturbing their proper relation to each other as they are arranged in lines and columns.

To this end the imposing-table, whether made from iron cast into shape, or from stone cut or otherwise fashioned, is provided all around its border edge with an offset or shoulder, 3, the surface of which is, at a distance below the plane 4 of the imposing-table, equal to the thickness of the bottom plate of

an ordinary galley, which shoulder or ledge affords a seat upon which to rest and support the mouth end of a galley when it is desired to transfer a mass of types from it to the table, or vice versa.

The drawing, in its sectional view, illustrates such a mass of types in a position where they are partially supported by the table and partially by the galley.

This provision for facilitating the transfer of composed matter from the galley wherein it is placed as it is emptied from the compositor's stick to the table where it is imposed and made up into a printing-form is important, since it entirely removes the danger of dropping either the body of types or portions of its lines when the same are picked up and carried to the table by one's hands; and this convenience is equally great in removing a body of types from the table where the form is unlocked to the galley where the mass of types is stored for distribution.

What, therefore, is claimed as new is—

An imposing-table the bed of which is provided with a border ledge or shoulder adapted to support the mouth end of a galley in such a position that the face of the table and inner surface of the galley shall lie in or nearly in the same plane, substantially as described.

In testimony whereof I have signed my name to this specification in the presence of two subscribing witnesses.

JOHN POLHEMUS.
